STRIP-SERVING MACHINE

Charles Walker, Knoxville, Tenn.

Application June 13, 1933, Serial No. 675,588

12 Claims. (Cl. 216—29)

My invention consists in new and useful improvements in a hand operated sealing device whereby any desired length of gummed strip or label may be fed from a magazine and quickly applied to a package or the like for sealing the same.

It is the object of my invention to provide a device of this character which may be grasped in one hand and the strip fed, moistened and severed without necessitating the use of the other hand.

Another object of my invention resides in the novel means for simultaneously and positively moistening the gummed surface of the strip as it is fed past the feeding roll.

15 A further object of my invention is to provide a form of knife which automatically severs the strip upon the release of the feeding means.

With the above and other objects in view which will appear as the description proceeds, my invention consists in the novel features herein set forth, illustrated in the accompanying drawings and more particularly pointed out in the appended claims.

20 Referring to the drawings in which numerals of like character designate similar parts throughout the several views,

Fig. 1 is a longitudinal sectional view of the device showing one form of cutting means.

Fig. 2 is a longitudinal section taken on line 2—2 of Fig. 1 with the feeding roll shown only partly in section.

Fig. 3 is a sectional detail taken on line 3—3 of Fig. 2.

Fig. 4 is a detail sectional view of the knife taken on line 4—4 of Fig. 1.

Fig. 5 is a detail view of one form of moistening device.

Fig. 6 is a sectional view taken on line 6—6 of Fig. 1.

40 Fig. 7 is a sectional detail of a modified form of moistening device.

Fig. 8 is a sectional view partly broken away illustrating a modified form of knife.

Fig. 9 is a sectional view taken on line 9—9 of Fig. 8.

Fig. 10 is a sectional view partly broken away, showing a modified form of feeding roll operating means, and

Fig. 11 is a sectional view taken on line 11—11 of Fig. 10.

In the drawings, 1 represents a substantially rectangular casing of such transverse dimensions that it can be easily grasped and held in one hand, the rear end wall of said casing being open 55 to receive a tank or reservoir 2 extending in said

casing for a greater portion thereof and being of less vertical dimension than said casing. The space above said reservoir forms a passageway 3 which extends the entire length of the casing 1. Adjacent the top of the rear wall of the reservoir, I provide a suitable inlet opening for filling the same with water, said opening being closed by a threaded plug or cap 4 having a small vent port 5. The reservoir is retained in position in the casing by means of a spring hook member 6 suitably secured to the side wall of the casing 1 as shown in Fig. 2.

At a suitable point remotely located from the casing 1 and connected thereto by means of a flexible conduit 7, I provide a magazine of 15 gummed strip 8, the flexible conduit terminating in a flaring or fan-shaped mouth 9 leading to the passageway 3 and being hingedly connected to the top wall of the casing as shown at 9a. As will be seen from Fig. 6, this flexible conduit 20 is cylindrical in cross section and as the flat strip is fed from the magazine, it is curled within the conduit, flattening out again as it reaches the flaring mouth 9. While I have shown the magazine located at a point separate and apart 25 from the casing 1, it is obvious that I may, if desired, employ a structure wherein the magazine is carried by the casing.

The side walls of the casing adjacent the forward end thereof are provided with suitable 30 openings adapted to receive flanged thickened closures 10 and 11 screwed or otherwise suitably secured to the casing, the inner faces of said closures being recessed as at 12 and 13, respectively, to form bearings for a transverse roller 35 or shaft 14, said roller being spirally grooved as at 14a to receive complementary spiral ridges on a spindle 15 projecting through a suitable opening in the closure 10. The outer end of the spindle is pivotally connected by means of a 40 bolt 16 to one end of an operating arm 17, substantially U-shaped in cross section, and extending longitudinally along the side wall of the casing 1, gradually curving outwardly therefrom adjacent its spindle engaging end, the other end 45 of said arm 17 being pivotally connected by means of a bolt 18 to a suitable bracket 19 mounted on the side wall of the casing at a point adjacent the rear extremity thereof.

Surrounding the roller 14 and being freely rotatable thereon, I provide a sleeve member 20 having a suitable transverse peripheral slot into which is inserted a pawl member 21 pivoted therein as at 22 for engaging a series of ratchet teeth 23 provided at an adjacent point on the 55

periphery of the inner roller 14, a suitable spring 24 normally holding the pawl in engaging position with the teeth 23. It will be noted that the teeth and pawl member are so disposed with respect to one another that the pawl member will only engage the teeth on the counterclockwise rotation of the inner roller 14. As shown in Fig. 2, the inner end of the sleeve 20 is provided with an annular series of teeth 25, a spring pawl 26 10 suitably secured to the casing normally engaging said teeth to prevent the clockwise rotation of the sleeve 20. It will be noted that the periphery of the sleeve 20 is provided with a rough surface to insure proper gripping of the strip 8. 15 A housing 27, suitably secured to the side walls of the casing 1, partially surrounds the sleeve 20 and terminates at one end in a rounded edge 28 forming a guide or support for the strip 8, the other extremity of said housing being squared to 20 form a cutting edge 29 for the purpose herein-after set forth.

Immediately above the sleeve 20, I provide an idler roller 30 freely rotatable on a transverse shaft 31 mounted in the side walls of the casing 1. If desired, I may employ suitable springs 25 normally tending to hold the idler roller 30 in engagement with the sleeve 20 to insure gripping of the strip 8.

As shown in Fig. 1, fins or the like 32 depending from the top wall of the casing 1 and being angularly disposed with respect thereto are provided in the passageway 3 for guiding the strip 8 and for preventing the same from buckling or turning up in the passageway.

The bottom wall of the casing merges into a substantially rounded front wall provided with a suitable outlet opening for the strip 8, immediately above which I provide a downwardly extending sealing member 33 pivotally mounted on a transverse shaft 34 and normally retained at a downward angle by a suitable spring 35. The strip engaging extremity of the sealing member 33 is preferably rounded as at 36 for applying the strip 8 to the package being sealed. This applying member may be in the form of a suitable roller attached to the strip engaging end of the sealing member 33, if desired.

The inner extremity 37 of the sealing member 33 extends longitudinally in the passageway 3 for a short distance and terminates in a vertically disposed transverse knife blade 38, whereby when the sealing member 33 is rocked upwardly on its pivot 34, the blade 38 will engage the complementary cutting edge 29 on the housing 27 and sever the strip 8. As shown in Fig. 4, the cutting edge of the knife 38 is preferably inclined upwardly towards one end to facilitate the cutting operation.

At a suitable point in the bottom of the front wall of reservoir 2, I provide an outlet connection 39 (Fig. 5) having a check valve 39a of any conventional form, said connection being adapted to receive one end of a flexible tube or conduit 40, which extends between the curved bottom wall of the casing 1 and the housing 27 to a point in close proximity to the undersurface of the strip 8 in front of the edge 29 of the housing. The flexible conduit 40 terminates in a flat flaring nozzle 41 provided with a series of small discharge openings 42 for the purpose hereinafter described. This nozzle 41 may be either integral with the conduit 40 as shown in Fig. 1, or detachable as shown in Fig. 5.

As clearly shown in Fig. 3, adjacent one side 75 of the flexible conduit 40, at a suitable point

intermediate the ends thereof, I provide a stationary block member 43 suitably secured to the side wall of the casing 1, and adjacent the other side of the flexible conduit 40 and in alignment with the block member 43, I provide a plunger 44 secured to one end of a reduced shaft or stem 45 which extends through a suitable opening in the side wall of the casing 1. The projecting end of said stem 45 is provided with a transverse slot adapted to receive the free end of a downwardly curved resilient arm 47 depending from the operating arm 17 and suitably secured thereto as at 48 (Fig. 2), whereby as the operating lever 17 is moved inwardly, the resilient arm 47 will in turn force the plunger 44 inwardly against the flexible conduit 40 and compress the same, thus causing the water in said conduit to be forced out through the small discharge openings 42 in a series of jets onto the moving strip 8, the backing up of the water into the reservoir being prevented by the check valve 39a. It will be noted that this resilient arm 47 serves also to automatically return the operating arm 17 to its outward position upon releasing the latter.

Having thus described the construction of the 25 preferred form of my invention illustrated in Figs. 1 to 5 of the drawings, its operation is as follows:—

Assuming that a package is wrapped and it is desired to seal the same. The device is grasped 30 in one hand and the operating arm 17 is moved inwardly, the spindle 15 engaging the complementary grooves in the inner roller 14 and causing the latter to rotate counterclockwise, and through the medium of the pawl member 21, 35 rotates the sleeve member 20 in the same direction, forcing the strip 8 forward between the sleeve 20 and the idler roller 30. Simultaneously with this operation, the resilient arm 47 connected to the operating lever 17 pushes the plunger 44 40 inwardly against the flexible conduit 40 and forces the water out through the discharge openings 42 in thin jets onto the moving strip 8. Upon the release of the operating lever 17, it will be 45 returned to normal position by the resilient arm 47, and the operation heretofore described will be repeated until the desired length of strip is fed.

It will be noted that as the strip is fed out of the device, it will be guided onto the package by 50 means of the sealing member 33, and when the desired length strip is obtained, this sealing member is forced against the package and rocked to its full extent on the pivot 34, causing the knife blade 38 to move down and sever the strip 8. 55

In Figs. 8 and 9, I have shown a modified form of knife actuated by the operating lever 17, and comprising a suitable knife member 49 extending through an opening in the closure 10 and being pivoted thereto as at 50, said knife being held in inoperative position by means of a spring 51 secured to the closure 10 in any convenient manner. The top edge of the knife member 49 is provided with a rounded projection or lug 52 adapted to be engaged by a hinged lug 53, pivoted as at 54 to the end of a substantially L-shaped rod 55 secured to the end of the operating lever 17 adjacent the spindle 15 with its free end extending for a short distance into the casing through a suitable opening in the closure 10.

In operation, the device is grasped in one hand and the operating lever 17 is moved inwardly, causing the strip 8 to be fed in the same manner as that shown in Figs. 1 to 5, hereinabove described. In this operation, the L-shaped rod 55 75

will also be moved inwardly and in passing over the projection 52 on the knife member 49, the hinged lug 53 will be swung in clockwise direction as shown in dotted lines in Fig. 9, without actuating the knife. It may be stated at this point that the hinged lug 53 is returned to operative or engaging position by any suitable spring means. Upon the release of the operating lever 17, the same will be brought back to its normal outward position in the same manner as described in Figs. 1 to 5, thus causing the lug 53 on the rod 55 to engage projection 52 on the knife blade 49 and force the latter downwardly against the complementary cutting edge 29 to sever the strip 3.

If a longer strip is desired than can be fed in one operation of the lever 17, the lever is reciprocated back and forth, the operator being careful not to completely release said operating lever until the proper length of strip is fed.

In Figs 10 and 11 I have shown a modified form of actuating means for the feeding roll which comprises an operating spindle 15a rotatably swiveled at one end 56 to the operating lever 17a and being spirally grooved to engage complementary grooves in the closure 10a, the free end of said spindle carrying an enlarged member 57 transversely slotted to receive a pawl member 58 pivoted as at 59 and adapted to engage a series of longitudinally extending teeth 60 provided in the central portion of sleeve member 20a, a small spring 61 normally forcing the pawl 58 outwardly to engage the teeth 60. As in the device shown in Fig. 2, one end of the sleeve member is provided with a series of teeth 25a engageable by spring pawl 26a to prevent reverse rotation of the feed roll.

In the operation of this form of my invention, upon forcing the operating lever 17a inwardly, the spindle 15a will engage the grooves in the closure 10a and be turned in a counterclockwise direction (Fig. 11), and through the medium of the pawl 58 engaging the teeth 60, will cause the counterclockwise rotation of the sleeve 20a. Upon the release of the operating lever 17a, the spindle 15a will be turned in a clockwise direction but due to the engagement of the teeth 25a by the spring pawl 26a, and to the direction of the pawl 58 and teeth 61, rotation of the sleeve 20a is prevented.

In Figure 7 I have shown a modification adapted to prevent the discharge of an excess quantity of fluid. This device comprises a small plunger member 62 projecting from the lower portion of member 44 and adapted to reciprocate in a suitable vertical slot provided in the lower portion of said member 44, said small plunger 62 being normally forced outwardly by a coil spring or the like 63.

In the top face of the block member 43, I provide a recess or notch 64 adapted to cooperate with the end of the small plunger 62, whereby upon the downward movement of member 44, the plunger 62 will engage the flexible conduit 40 in advance of member 44 and when the latter is finally brought into compressing position, the requisite amount of fluid has been trapped in the discharge end of the conduit through the co-operation of the plunger 62 and recess 64.

From the foregoing it is believed that the construction and advantages of my invention may be readily understood by those skilled in the art without further description, it being borne in mind that numerous changes may be made in the details disclosed without departing from the spirit

of the invention as set out in the following claims.

I claim:—

1. A hand operated gummed strip applying device comprising a casing housing a liquid reservoir, a strip discharge opening in said casing, a strip feeding element adjacent said discharge opening, actuating means for said feeding element for feeding a gummed strip through said opening, a conduit leading from said reservoir to a point in close proximity to the gummed side of said strip, posterior to said feeding element, means operable by and simultaneously with said feed actuating means for spraying liquid through said conduit onto said strip, and means for severing said strip. 10

2. A hand operated gummed strip applying device comprising a casing housing a liquid reservoir, a gummed strip magazine located at a point remote from said casing, a flexible conduit leading from said magazine to said casing, a strip discharge opening in said casing, a strip feeding element adjacent said discharge opening, actuating means for said feeding element for feeding said gummed strip through said opening, a flexible conduit leading from said reservoir to a point in close proximity to the gummed side of said strip, posterior to said feeding element, means operable by and simultaneously with said feed actuating means for spraying liquid through said conduit onto said strip, and means for severing said strip. 15

3. A hand operated gummed strip applying device comprising a casing housing a liquid reservoir, a strip discharge opening in said casing, a strip feeding element adjacent said discharge opening, actuating means for said feeding element for feeding a gummed strip through said opening, a flexible conduit leading from said reservoir to a point in close proximity to the gummed side of said strip, posterior to said feeding element, means operable by and simultaneously with said feed actuating means for spraying liquid through said conduit onto said strip, and means for severing said strip. 20

4. A hand operated gummed strip applying device as claimed in claim 3 wherein the discharge end of said flexible conduit terminates in a flat flaring end provided with a plurality of restricted 25 openings. 40

5. A hand operated gummed strip applying device comprising a casing housing a liquid reservoir, a strip discharge opening in said casing, a strip feeding element adjacent said discharge opening, a liquid spraying device connected with said reservoir and arranged in close proximity to the gummed side of said strip posterior to said feeding element, hand pressure actuated means for operating said feeding element for feeding a 30 gummed strip through said opening, means operable by and simultaneously with said hand pressure actuated means for operating said spraying device, and means for severing said strip. 55

6. Apparatus as claimed in claim 5 wherein 60 said last named means comprises a knife pivotally mounted in said casing adjacent said discharge opening and means operable upon the release of said hand pressure actuated means for operating said knife. 65

7. Apparatus as claimed in claim 5 including a sealing member pivotally connected to said casing, the means for severing said strip being carried by and operable by said sealing member. 70

8. A hand operated gummed strip applying 75

device comprising a casing housing a liquid reservoir, a gummed strip magazine located at a point remote from said casing, a flexible conduit leading from said magazine to said casing, a strip discharge opening in said casing, a strip feeding element adjacent said discharge opening, actuating means for said feeding element for feeding said gummed strip through said opening, a flexible conduit leading from said reservoir to a point in close proximity to the gummed side of said strip, posterior to said feeding element, means operable by and simultaneously with said feed actuating means for spraying liquid through said conduit onto said strip, a sealing member pivotally mounted on said casing adjacent said strip discharge opening, and means operated by said last named member for severing said strip.

9. A hand operated gummed strip applying device comprising a casing housing a liquid reservoir, a strip discharge opening in said casing, a strip feeding element adjacent said discharge opening, a conduit leading from said reservoir to a point in close proximity to the gummed side of said strip; posterior to said feeding element, hand pressure actuated means for operating said feeding element for feeding a gummed strip through said opening, means operable by and simultaneously with said hand pressure actuated means for spraying liquid through said conduit onto said strip, and means for severing said strip.

10. A hand operated gummed strip applying device comprising a casing housing a liquid reservoir, a strip discharge opening in said casing, a strip feeding element adjacent said discharge opening, a conduit leading from said reservoir to a point in close proximity to the gummed side of said strip, posterior to said feeding element, hand pressure actuated means for operating said feeding element for feeding a gummed strip through said opening, means operable by and simultaneously with said hand pressure actuated means for spraying liquid through said conduit onto said strip, a sealing member pivotally mounted on said casing adjacent said strip dis-

charge opening, and means operated by said last named member for severing said strip.

11. A hand operated gummed strip applying device comprising a casing housing a liquid reservoir, a strip discharge opening in said casing, a strip feeding element adjacent said strip discharge opening, hand pressure actuated means for operating said feeding element for feeding a gummed strip through said opening, including a spirally grooved spindle extending within said strip feeding element and adapted to engage complementary mechanism in the latter, a lever pivotally mounted at one end to said casing, its other end operatively engaging said spindle, means operatively associated with said lever for spraying liquid from said reservoir onto said gummed strip simultaneously with the operation of said strip feeding element, and means for severing said strip.

12. A hand operated gummed strip applying device comprising a casing, a liquid reservoir in said casing, a passageway lying between said reservoir and one wall of said casing, a strip inlet for said passageway, a strip discharge opening in said passageway, a strip feeding element adjacent said discharge opening, a housing for said feeding element, one edge of said housing forming a guide for said strip, the other edge of said housing forming a cutting edge, a flexible conduit leading from said reservoir to a point in close proximity to the gummed side of said strip, posterior to said feeding element, hand pressure actuated means for operating said feeding element for feeding a gummed strip through said discharge opening, including a spirally grooved spindle extending within said strip feeding element and adapted to engage complementary mechanism in the latter, a lever pivotally mounted at one end to said casing, its other end operatively engaging said spindle, a sealing member pivotally mounted adjacent said strip discharge opening, and cutting means operated by said last named member and co-acting with said cutting edge on said housing, for severing said strip.

CHARLES WALKER. 45
